UNITED STATES PATENT OFFICE.

JAMES MALCOLM HAMILTON VENOUR, OF LONDON, ENGLAND.

VELOCIPED.

SPECIFICATION forming part of Letters Patent No. 634,043, dated October 3, 1899.

Application filed November 22, 1898. Serial No. 697,185. (No model.)

To all whom it may concern:

Be it known that I, JAMES MALCOLM HAMILTON VENOUR, cycle-manufacturer, a subject of Her Majesty the Queen of Great Britain, residing at 149 New Kent road, London, England, have invented certain new and useful Improvements in Velocipedes, (for which I have applied for a patent in Great Britain, No. 21,667, dated October 14, 1898,) of which the following is a specification.

My invention relates to improvements in the construction of the steering-head and the front or steering fork of safety-bicycles, tricycles, motor-driven and other velocipedes, and front-steering road-vehicles, and has for its object to so strengthen the said head and fork as to prevent the breaking of same when in use and so obviate the many fatal or otherwise serious accidents that have been known to occur from such breakages.

The cycle industry has exercised much study in endeavoring to find means for strengthening the front fork of such machines, and many devices have been introduced with a view to this end, all of which have been attended with some technical objection—such, for instance, as adding too much to the weight of the vehicle or by enlarging the crown for carrying larger or extra members of the said fork to so extend the width of the said fork as to unduly limit the area or arc through which the same was allowed to oscillate in steering the machine; but according to my invention I am enabled to materially strengthen the said fork without increasing its weight to any appreciable extent or decreasing the area through which the steering-wheel may oscillate.

In order that my said invention may be fully understood, reference is hereinafter made to the accompanying drawings, of which—

Figures 1 and 2 are side and front elevations, respectively, of the front fork and steering-head of a bicycle or tricycle according to my invention. Fig. 3 is a much-enlarged plan view of the upper end of the said steering-head, while Figs. 4 and 5 are like enlarged but sectional views upon the lines A B and C D, respectively, of Figs. 1 and 2, Fig. 6 being a diagram illustrating the arc through

which the said steering-wheel of such a fork is free to oscillate.

In carrying my invention into effect I prefer to employ two or more parallel plates, such as A and B, in the construction of the fork-crown, these being alike in shape and configuration and approximately that shown by the enlarged views, Figs. 4 and 5, in the lower one or ones of which I provide four holes C C' and D D', all formed in the shape of an elongated ellipse and so arranged in position in the said plate or plates B that those C C' are one behind the other at the right, while those D D' are one behind the other at the left, hand sides of the said plates, and through the holes C C', I pass a pair of tubes E and E' of the same shape in cross-section as the said holes and brazed or otherwise connected to the plate or plates B and the plate A or suitable liners thereon, the said tubes being so formed longitudinally as to be brazed or otherwise connected together at their lower ends to form the right-hand half of the front or steering fork and collectively adapted at a to receive and be connected to the right-hand end of the spindle of the steering-wheel in the usual way, and in precisely the same manner a pair of tubes F and F' pass through and are fixed to the holes D and D' in the plate or plates B and the plate A and are connected at their lower ends to form the left-hand half of the same fork and collectively adapted at b to receive and carry the left-hand end of the spindle of the said wheel. As previously stated, the said plate or plates B and the plate A are of approximately the same shape, and I provide in the front of these holes c and d, respectively, for the passage of the brake-rod and in the center of the back of A a circular hole, through which passes the lower end of a preferably tubular standard G, brazed or otherwise connected thereto and the plate or the uppermost plate B with or without passing through the latter, and over or partly over the holes C C' and D D' in the plate or plates B, I mount and fix upon and braze or otherwise connect to the plate A the lower ends of a pair of tubular pillars H and H', the position of the said tubes being such as to form the base of an imaginary isosceles triangle, the apex of which is the axial center of the tube

G, while the sides are at an angle of sixty degrees or thereabout with the said base. The said tubular pillars H and H' are open at their upper ends for the reception of the handle-bar J, having upon its under surface two lugs or projections K and K', which dip into H and H' and are therein secured by set-screws or their equivalents L, the upper ends of H and H' being connected together and to the tube G by a tie-plate M or by any other suitable means, by which the rigidity of the upper end of these may be secured.

The standard G fits within the steering-tube O of the frame of the machine P (shown in dotted outline in Fig. 2) and is secured in position thereon by the means of a split ring or cap R, having lugs R' and R'', brought together by a through-bolt S, the said ring or cap R having connected thereto or formed therewith a shoulder T, which normally rests upon the top of the steering-tube O when the said ring or cap is fixed upon the upper end of G.

It will therefore be understood that the front or steering fork according to my invention is composed of four tubes or rods arranged in pairs E E' and F F', with the tubes in each pair placed one behind the other, each pair being ultimately connected together at their lower ends and at their upper ends or fork-crown by two or more plates B and the plate A, and by these means each side of the fork is strengthened in the direction in which the breaking strain occurs—namely, fore and aft or in the direction of the arrow in Fig. 2—in addition to which the steering-head is further strengthened by the triangular position of the three tubes G and H and

H', upon the former of which the oscillation of the steering-wheel is centered, and by reason of such formation of the steering-head the arc through which this is allowed to oscillate in the steering of the vehicle is that shown by dotted outline in Fig. 6 or substantially from X to X.

Having now ascertained the nature of my invention, what I claim is—

In an improved front or steering fork and head, for the front steering-wheel of velocipedes and other vehicles, the combination of two pairs of tubes or rods E E' and F F' the members of each pair being placed one behind the other, with each pair joined at their lower ends to a spindle attachment a and b, and connected at their upper ends or crown by plates B and A, the said plates forming guides c and d for the brake-rod, and arranged to carry tubes H and H' and G, so placed relatively to each other that lines connecting the centers of the tubes will form a triangular figure, and connected at their upper ends by a plate M or the like, the said tube G in combination with the steering-tube of the machine forming the fulcrum of the said steering-wheel, the said tubes H and H' receiving and holding the handle-bar J, having extensions K and K' for engaging with the said tubes, substantially as herein described and shown by the appended drawings.

In witness whereof I have hereunto set my hand in presence of two witnesses.

JAMES MALCOLM HAMILTON VENOUR,
